US00D997920S

(12) United States Design Patent **(10) Patent No.:** **US D997,920 S**
Okuley **(45) Date of Patent:** **** Sep. 5, 2023**

(54) ELECTRONIC DEVICE

(71) Applicant: **Intel Corporation**, Santa Clara, CA (US)

(72) Inventor: **James Okuley**, Portland, OR (US)

(73) Assignee: **Intel Corporation**, Santa Clara, CA (US)

(**) Term: **15 Years**

(21) Appl. No.: **29/676,258**

(22) Filed: **Jan. 9, 2019**

(51) LOC (14) Cl. **14-03**

(52) U.S. Cl.

USPC **D14/248**

(57) CLAIM

The ornamental design for “electronic device”, as shown and described.

DESCRIPTION

FIG. 1 is a right, front perspective view of an electronic device.

FIG. 2 is a front view of the electronic device of FIG. 1.

FIG. 3 is a rear view of the electronic device of FIG. 1.

FIG. 4 is a right side view of the electronic device of FIG. 1.

FIG. 5 is a left side view of the electronic device of FIG. 1.

FIG. 6 is a top view of the electronic device of FIG. 1; and,

FIG. 7 is a bottom view of the electronic device of FIG. 1.

The rear, right side, left side, top, and bottom views of the electronic device of FIG. 8 are the same as those for the electronic device of FIG. 1.

The features shown in broken lines depict portions of the electronic device that form no part of the claimed design.

1 Claim, 5 Drawing Sheets
